UNITED STATES PATENT OFFICE.

CHAUNCEY B. FORWARD, OF URBANA, OHIO.

COMBINED FURNACE AND BOILER AND STEAM-SUPERHEATER.

1,251,880.

Specification of Letters Patent.

Patented Jan. 1, 1918.

Application filed June 13, 1917. Serial No. 174,456.

To all whom it may concern:

Be it known that I, CHAUNCEY B. FORWARD, citizen of the United States, residing at Urbana, in the county of Champaign and State of Ohio, have invented certain new and useful Improvements in Combined Furnaces and Boilers and Steam-Superheaters, of which the following is a specification.

- 10 My invention has reference to a steam boiler and superheater, and the object of the invention is to provide means to obtain and maintain a high superheat with a minimum of wear and repair to the boiler and 15 superheating coils, said means involving the use of an auxiliary superheating coil in a particular way and relation substantially as herein shown and described and more particularly pointed out in the claims. The 20 invention is of especial utility in connection with my apparatus for refining oils as shown and described in another application filed concurrently herewith and bearing Serial Number 174457, but is not necessarily 25 limited to such use and apparatus.

In the accompanying drawings, Figure 1 is a sectional elevation front to rear of a high pressure steam boiler and superheater constructed according to my invention. Fig. 30 2 is a sectional elevation of the said parts at right angles to Fig. 1 and corresponding substantially to the irregular line 2—2 on said figure.

As thus shown, the steam boiler B in its 35 entirety consists of the furnace walls F and the drums 2 and connecting tubes 3 supported within said walls above the bridge wall W and arch A and the grates G. This 40 particular boiler also has its water tubes extending in incline relation to the bridge wall and is separated at intervals by division walls D to produce a circuitous travel of the heat generated within the furnace, and the area of highest temperature is 45 approximately at the throat T between arch A and the bridge wall. The steam superheater set into this organism is of a dual character and comprises a primary heater 4 made of coils of pipe and a secondary or 50 auxiliary coil heater 5 with a pipe 7 connecting said members to convey the steam from the primary heater to the secondary heater while a pipe 6 from the uppermost drum 2 feeds the steam under pressure 55 to the primary heater 4. The discharge of the superheated steam from secondary

heater 5 is by pipe 8 from the secondary heater to the place of use, which is not shown herein but may, as an example, be supposed to be a hydrocarbon oil heating 60 and separating apparatus as shown and described in my co-pending application above set forth.

The superheaters 4 and 5 operate together more effectively to superheat the steam than 65 where only a single superheating coil 4 is used in the flue between the tubes about wall D, or where only a single heating coil 5 is placed in the throat T. It must be understood that operations proceed under high 70 pressure and temperatures, and if superheater 4 were relied upon alone a higher degree of firing would be required, or if this large main coil 4 were used at the throat T, the throat would be choked. 75 Moreover, the secondary coil 5 is in an area of higher temperature than primary coil 4, and for that reason the main coil 4 will last longer and the wear fall upon the smaller coil 5 which is in a convenient place 80 to be repaired or removed and replaced. The best working position of secondary coil 5 is also easily ascertained for any given need that is, it may be placed nearer to or farther from throat T to superheat the 85 steam to a temperature which will combine with the high pressure needed for my purpose. In this way, the secondary superheater 5 supplements the primary heater 4 to give the maximum pressure and superheat 90 with the most economical fuel consumption and a minimum of repair and cost of maintenance.

In respect to location of the primary superheating coil 4, it will be noticed that it 95 overhangs the top of the first of the two baffle walls D and in such manner that it is exposed directly to the heat flowing over the top of said wall, and the secondary or auxiliary coil 5 lies beneath or in front of 100 the lower and inner bank of circulating pipes or tubes 3 of the boiler and in such position thereto and to the arch of the furnace over the grate bars G and in respect to throat T that the entire coil is exposed 105 to the direct heat from the furnace, as it rebounds from the wall w and flows upward along the bank of boiler tubes 3 under which the said secondary coil is located.

What I claim is:

1. A furnace having an inclosing wall and a steam boiler therein having a plurality of

110

- banks of steam circulating tubes and baffles between the same successively, in combination with steam superheating units consisting each of coils of pipe having pipe connection and one of said coils located behind the front bank of boiler tubes and relatively over the first of said baffles and the other coil in the throat of the furnace across the front of said first bank of tubes.
- 10 2. A furnace having an inclosing wall and a steam boiler therein comprising a series of banks of steam circulating tubes and baffle walls between the same, in combination with a primary and a secondary

superheating unit consisting each of coils 15 of pipe having pipe connection and the said primary unit disposed between the first and the second banks of tubes and over the top of the baffle intervening said tubes and with a portion at either side thereof, and the 20 secondary coil disposed across the front of the first bank of tubes at the inner end of the wall over the fire grate and relatively at the point of greatest heat.

Signed at Cleveland, in the county of 25 Cuyahoga, and State of Ohio, this 8th day of June, 1917.

CHAUNCY B. FORWARD.
